UNITED STATES PATENT OFFICE.

PATRICK FLAHERTY, OF JEROME, ARIZONA TERRITORY.

DESIGN FOR A WATCH-FOB.

No. 38,321.

Specification for Design.

Patented Nov. 27, 1906.

Application filed September 25, 1906. Serial No. 336,209. Term of patent 3½ years.

To all whom it may concern:

Be it known that I, PATRICK FLAHERTY, a citizen of the United States, residing at Jerome, in the county of Yavapai and Territory of Arizona, have invented a new, original and ornamental Design for Watch-Fobs, of which the following is a specification, reference being had to the accompanying drawing, forming part thereof.

The figure illustrated is an elevation of my new design.

The design comprises a pendent bar inscribed with ornamental letters to which is attached a ribbon provided with an ornamental

tal inscription. Secured to the bottom of this ribbon is an ornamental charm with an inscription thereon.

I claim—

The ornamental design for a watch-fob, as shown and described.

In witness that I claim the foregoing I have hereunto subscribed my name this 18th day of September, 1906.

PATRICK FLAHERTY.
